No. 622,011.

Patented Mar. 28, 1899.

J. NATTERER.
SPEED REGULATOR.

(Application filed Feb. 11, 1899.)

(No Model.)

UNITED STATES PATENT OFFICE.

JOSEF NATTERER, OF JERSEY CITY, NEW JERSEY, ASSIGNOR TO THE SYMPHONION MANUFACTURING COMPANY, OF NEW YORK, N. Y.

SPEED-REGULATOR.

SPECIFICATION forming part of Letters Patent No. 622,011, dated March 28, 1899.

Application filed February 11, 1899. Serial No. 705,302. (No model.)

To all whom it may concern:

Be it known that I, JOSEF NATTERER, a citizen of the United States, residing at Jersey City, in the county of Hudson and State 5 of New Jersey, have invented certain new and useful Improvements in Speed Regulators for Music-Boxes, of which the following is a specification.

This invention relates to speed-regulators 10 for music-boxes, the object of the same being to produce a simple, reliable, and durable speed-regulator for the purpose of controlling the movements of the motor, so that a piece of music can be played slow or fast, as desired.

15 The invention consists of a suitably-supported regulator-shaft connected with the motor and supported in any suitable manner, a guide-plate arranged on the shaft, vanes guided inwardly or outwardly relatively to each other upon said guide-plate, a vane-controller sliding on said shaft, means for actuating said controller, and suitable means of connection between said controller and the vanes, whereby the same are moved so as to 20 offer more or less resistance to the air, as will be hereinafter clearly described and then particularly claimed.

25 In the accompanying drawings, Figure 1 is a front elevation of my improved speed-regulator for music-boxes, showing the vanes in their innermost position, so as to offer the least resistance to the air. Fig. 2 is a section on the line 2 2 of Fig. 1. Fig. 3 is a similar view to Fig. 1, parts broken away, showing the vanes in their outermost position for offering the greatest resistance to the air. Fig. 4 is an enlarged section on the line 4 4, Fig. 3. Fig. 5 is an enlarged section on the line 5 5, Fig. 3; and Fig. 6 is a detail perspective view 30 of the guide-plate for the vanes.

Similar letters of reference indicate corresponding parts.

Referring to the drawings, A indicates the bracket-frame for supporting the working 45 parts of the speed-regulator and which is attached in proper position in the music-box for enabling the regulator to control the speed of the motor.

B indicates the motor-shaft, and B' a worm-50 wheel mounted on said shaft, which shaft turns in a bearing furnished by the plate B², fixed to the bracket.

Journalized at one end in a suitable bearing in one arm A' of the bracket-frame A and at the other end in a plate or support A², fixed 55 to the bracket, is a shaft C, which is provided with a worm C', that meshes with the teeth of the worm-wheel B'.

Held on the shaft C by friction or in any other suitable manner is the guide-plate D, 60 said plate being provided with wings D' D², which, as shown clearly in Figs. 5 and 6, are offset relatively to each other or, in other words, lie in parallel planes. The wings D' D² are connected together by means of curved 65 connecting portions d d', which are respectively curved in opposite directions, so as to form a sort of hub which can slip over the shaft. The guide-plate is formed by slitting the same at the central portion and then opening out the connecting portions d d' in opposite directions, so that the wings of the guide-plate are offset. In this way by striking up 70 the connecting portions d d' from the body of the plate the same are enabled to have a certain spring action, so that the parts d d' will have a frictional contact with the shaft and hold the guide-plate in position. Upon the opposite sides of the wings D' D² of the guide-plate guide-flanges d² d³ are formed. These 75 flanges are produced by bending the edges of the wings inwardly, as shown in Fig. 6.

Guided upon the opposite surfaces of the wings D' D² are vanes E, the inner ends of said vanes being received within said flanges 85 and the outer ends of the same being bent or curved outwardly in opposite directions. The vanes E can be moved inwardly or outwardly 90 relatively to each other along the opposite surfaces of the guide-plate by suitable means, presently to be described, the movements of the vanes being limited by means of headed studs or pins e thereon, which pass through slots e', formed in both wings of the guide-plate D.

95 F indicates a vane-controller, which is provided with a hub F' for guiding the controller upon the shaft C. The hub of the controller is arranged within the open middle portion d' of the guide-plate, while the opposite ends of the controller are provided with converging slots f, which receive the studs or pins e. When the controller is slid along the shaft C, the slotted ends f, in connection with the studs

e, produce the sliding movement and adjustment of the vanes of the regulator.

- f' f'* indicate annular flanges formed on the hub *F'*, and into the groove or space formed 5 between the flanges a finger *g* on the inner end of an actuating-pin *G*, guided in the arm *A'* of the bracket, projects, so that the reciprocation of the actuating-pin produces a corresponding movement of the vane-controller. 10 The actuating-pin is provided at its outer end with a laterally-projecting stud *g'*, that is received by an oblique slot *h* in the inner end of a slide or push-piece *H*, which is guided in its inward and outward movements by means 15 of a guide-pin *I*, mounted on the bracket and extending into a longitudinal slot *i* in said slide.

The parts of the regulator can be readily detached for repair, inasmuch as the ends of 20 the regulator-shaft are formed with pivots *C'*, one of which can be fitted in the bearing furnished in the arm *A'*, while the other end of the same can be fitted in the bearing furnished by the plate *A²*, which, being of spring 25 metal, can be sprung away from the shaft, so that the latter can be removed. The bearing in the arm *A'* is furnished by means of a bushing *k*, fitted in an opening in the end of the arm *A'*, a bearing-piece *k'*, and a closing- 30 plug *k²* on the end of the clip *K*, which is fastened in any suitable manner, as by means of a screw *k³*, to the arm *A'*. This construction of bearing permits the parts of the same to be renewed and enables an easy running of 35 the speed-regulator.

The parts of the regulator can be readily oiled when necessary, and they are all connected so that they can easily work together with no binding action.

- 40 In the position shown in Fig. 1 the speed of the motor is normal, as it is not influenced except by the customary position of the vanes. To reduce and regulate the speed of the motor of the music-box, an inwardly-reciprocating motion is imparted by hand to the slide *H*, so that the inclined walls of the slot *h* will impart an inward movement to the actuating-pin *G*, thereby moving the vane-controller inwardly and causing, by reason of the pin- 45 and-slot connection *e f*, the outward movement of the vanes *E* upon their guide-plate. In Fig. 3 the extreme limit of outward movement which can be imparted to the vanes is shown, and it is evident that according to the 55 different distances to which the vanes are adjusted from each other the speed of the motor will be regulated and varied.

Having thus described my invention, what I claim as new, and desire to secure by Letters 60 Patent, is—

1. In a speed-regulator for music-boxes, the combination, with a bracket-frame, and a shaft suitably journaled therein and adapted to be geared with the motor, of a guide-plate mounted 65 on the shaft and provided with outwardly-extending wings, vanes guided upon said

guide-plates, a longitudinally-movable vane-controller mounted on the shaft, suitable means of connection between the vane-controller and the vanes, and means for adjusting said vane-controller and vanes, substantially as set forth. 70

2. In a speed-regulator for music-boxes, the combination, with a bracket-frame, and a shaft suitably journaled therein and adapted to be 75 connected with the motor, of a guide-plate mounted on said shaft, said guide-plate having offset wings, vanes guided upon opposite sides of said guide-plate along said wings, and means for increasing or lessening the distance between the vanes, substantially as set forth. 80

3. In a speed-regulator for music-boxes, the combination, with a bracket-frame, and a shaft suitably journaled in said frame and adapted 85 to be connected with the motor, of a guide-plate mounted on said shaft and provided with guide-flanges at its edges upon opposite sides thereof, vanes guided in said flanges, and means for increasing or lessening the distance between said vanes, substantially as set forth. 90

4. In a speed-regulator for music-boxes, the combination, with a bracket-frame, and a shaft suitably journaled in said frame and adapted 95 to be connected with the motor, of a guide-plate mounted on said shaft, vanes guided upon said guide-plate, a vane-controller sliding on said shaft, suitable connection between the vane-controller and the vanes for moving 100 the vanes relatively to each other, an actuating-pin for actuating said controller, and means for moving actuating-pin, substantially as set forth.

5. In a speed-regulator for music-boxes, the 105 combination, with the bracket-frame, and a shaft journaled in said frame and adapted to be connected with the motor, of a guide-plate mounted on the shaft, vanes guided on said guide-plate, a vane-controller provided with 110 converging slots, studs projecting from the vanes into said slots, and means for moving said vane-controller upon the shaft, substantially as set forth. 110

6. In a speed-regulator, the combination, 115 with the bracket-frame and a shaft suitably journaled in said frame and adapted to be connected with the motor, of a guide-plate mounted on the shaft and provided with slots, vanes guided on said plate and provided with 120 headed studs projecting into said slots, a vane-controller sliding on the shaft and provided with converging slots also receiving said headed studs, and means for sliding said vane-controller, substantially as set forth. 125

In testimony that I claim the foregoing as my invention I have signed my name in presence of two subscribing witnesses.

JOS. NATTERER.
